UNITED STATES PATENT OFFICE.

ROBERT L. COCHRANE, OF CHICAGO, ILLINOIS, ASSIGNOR TO NATIONAL LOCK WASHER COMPANY, OF NEWARK, NEW JERSEY, A CORPORATION OF NEW JERSEY.

NUT LOCK.

1,427,194.

Specification of Letters Patent. Patented Aug. 29, 1922.

Continuation of application Serial No. 464,676, filed April 26, 1921. This application filed November 29, 1921. Serial No. 518,827.

To all whom it may concern:

Be it known that I, ROBERT L. COCHRANE, a citizen of the United States, residing at Chicago, in the county of Cook and State 5 of Illinois, have invented certain new and useful Improvements in Nut Locks, of which the following is a specification.

This invention pertains to nut locks of the lock washer type, and more particularly 10 to those of the split spring type, wherein the resiliency or spring of the washer is depended upon to effectively resist the force of compression. The most successful lock washers on the market at the present time 15 consist of a spiral segment having its end portions and intermediate parts bent, twisted, or displaced. The spiral curvature of the lock washer, when considered as a whole, is, however, maintained.

20 The present nut lock or lock washer, in its preferred form, does away with the spiral formation and, by reason of the contour imparted to its body, there is produced a structure which under actual test and strain 25 is found to be much superior to the spiral lock washer or any lock washer heretofore known.

The lock washer, or nut lock, forming the basis of the present application is adapted 30 particularly for use in connection with rail joints, although it is not necessarily limited to such use. Several forms of the invention are illustrated in the accompanying drawings, wherein—

35 Figure 1 is a plan view of the lock washer; Figs. 2, 3, and 4 edge or side elevations, as viewed in the direction of the arrows 2, 3, and 4, respectively;

40 Fig. 5 a transverse section on the line V—V of Fig. 1;

Fig. 6 a development of the lock washer;

Fig. 7 is a development of a modification;

45 Fig. 8 is a development of a further modification; and

Fig. 9 is a section of a rail joint.

The body of the lock washer is formed 50 of steel stock, and may be produced in any suitable manner, as, for instance, coiling the stock edgewise about a mandrel and then cutting it so as to produce lock washers. The several lock washers will, when thus made, have a spiral form, but during the course of manufacture such spiral formation 55 is eliminated and the body, intermediate its

ends, is deformed or thrown face-wise out of its normal line or plane, so as to produce a series of inter-connected, reversely-directed or reversely curved sections, with the ends inclined in opposite directions. 60

To illustrate the action of the lock washer, I have shown a rail joint in Fig. 9, consisting of the rail R, joint bars J, bolt B, nut N, and lock washer or nut lock W.

It is recognized that the theoretically 65 perfect rail would be a continuous one. This condition being impossible in practice necessitates the adoption of a structure which approximates as closely as possible the theoretical, desired end. When the ends 70 of the rails are deflected by the heavy rolling stock passing over the rail joint there is a distinct tendency to force the joint bars apart, thereby developing high tensile stresses in the bolts. This force is devel- 75 oped as a result of the engagement of the joint bars with the inclined under head of the rail and the inclined upper surface of the base, resulting in a wedging action. One function of the nut lock or lock washer 80 is to maintain the bolt normally under considerable tension and to absorb the stresses due to the increased tension of the bolt when the wheels are passing over the rail joint or when the expansion of the rails, due to heat- 85 ing, causes the joints to lift or move laterally, or when for other reasons the rail joint is subjected to abnormal conditions. By absorbing this additional load the bolts are prevented from being stressed beyond 90 their elastic limit, the resiliency of the washers enabling them to maintain said bolts under high tension after the abnormal load has been released. Thus, there is in- 95 cluded in the bolted joint construction a lock washer or nut lock which, through its highly developed resiliency, adequately op- 100 poses the movements referred to. Any movement of the rail ends results in wear of the several parts of the rail joint, in- 105 cluding the rail itself. By reducing this movement to a minimum the wear of the bolted joint parts and the rail ends is re- duced accordingly. The further function of the lock washer is to prevent turning of the nut on the bolt.

The ends of the nut lock, or lock washer, are designated 1 and 2 and are inclined, preferably, in reverse directions. Intermediate said ends the body of the lock washer 110

is sinuous in outline. There it thus produced a series of interconnected wave-like elements 3, as best seen by reference to Fig. 6, the curves being, preferably, evenly disposed and of the same height and depth with reference to a center line as I—I. Stated in another way, the crests of the upper curves preferably lie in one plane and the bottoms or outer faces of the opposite 10 or lower curves preferably lie in a second plane. Said planes are denoted in Fig. 6 as II—II and III—III, and, as will be seen, they are parallel and represent the bearing faces of the nut and the underlying cooperative member with which the lock washer 15 coacts. The curves are synergetic in their action, in that they work together or cooperate in setting up resistance to the nut, which is turned down upon the lock washer. 20 Preferably, with a lock washer of ordinary size, three crests will be present on each face of the device, said crests, with one of the lock washer ends, thus producing four 25 points of contact on each face or side of the lock washer, but the number of these crests and points of contact may be varied to suit the demands of the occasion.

Also, it is not necessary that the points of contact on either side of the medial plane 30 should be in the same plane, since the sinuosity of the interconnected wave-like elements may be varied and a high resistance to compression still be maintained. Such construction is shown in Fig. 7. With this 35 construction, as the nut is tightened on the bolt, the higher crests are engaged first, and, after a slight deformation, all of the crests are engaged and thereafter the action of all the wave-like elements is synergetic.

40 The lock washer in each case may be said to contain a series of short curved portions, each portion being of such a length as to offer a substantial resistance to a face-wise applied force, which would tend to straighten or flatten the same.

In the form shown in Fig. 8 the adjacent ends are substantially opposite each other, instead of being bent away from each other. While this structure does not engage the 50 opposing surfaces as effectively as the previous structures, it is, nevertheless, suitable for certain classes of service.

Lock washers made in accordance with the disclosure herein have shown very great 55 resistance to compression. The steel from which the lock washers are made has been evolved with reference to its highly developed physical properties. Washers in service, made of special grades of nickel- 60 chromium steel and others of titanium steel, have shown excellent results. Other modern steels may be used under proper conditions, particularly high carbon steels. In actual tests, specimens of these lock washers 65 were compressed and released many times

with a maximum pressure of 60000 pounds without impairing their efficiency, whereas previously known lock washers flatten and lose their efficiency at far less pressure. Among other tests, made to determine the 70 deflection under pressure of early specimens of my improved lock washer, is the following:

Load in pounds.	Deflection in inches.	
2000	0.004	75
4000	0.008	
6000	0.012	
8000	0.016	
12000	0.024	
16000	0.028	80
20000	0.033	
22000	0.036	
24000	0.038	
36000	0.040	
28000	0.043	85
30000	0.045	
32000	0.048	
34000	0.052	
36000	0.054	
38000	0.057	90
40000	0.062	

Assuming, for illustration, that a given bolt is capable of withstanding a tensile stress of 40000 pounds and is subjected to 95 this stress in service, I am to provide a lock washer capable of exerting an equal reaction or pressure without flattening, and also one which will recover and continue to exert its resistance to compression under load. 100 This is accomplished with my improved lock washer or nut lock. As a result the rails become practically continuous.

This application is filed as a substitute for my pending application Serial No. 105 464,676, filed April 28th, 1921, for improvements in nut locks.

What I claim is:

1. A spring lock washer having in plan 110 the shape of a split ring, the ends of the washer being deflected in opposite directions with the body portion intermediate such ends formed into a series of interconnected synergetic curves, the crests of said curves and one end of the body being in one plane 115 on one side of the medial horizontal plane of the washer and the crests of the curves and the end of the washer on the opposite side of said medial plane being likewise in one plane, the planes being all parallel.

2. A nut lock comprising a washer made 120 of spring metal of the character specified, having in plan the shape of a split ring, the ends of the washer being deflected in opposite directions, and the body portion intermediate such ends formed into a series of interconnected synergetic curves which alternately extend on opposite sides of the medial horizontal plane of the washer, said curves merging into each other with no intervening 125

flat portions, the maximum crest portions of said curves and the end of the washer on one side of said medial plane and the maximum crest portions of said curves and the end of 5 the washer on the other side of said medial plane being respectively in two planes only which planes are parallel to each other and to said medial plane.

3. The combination with a rail joint, comprising the abutting rail ends, joint bars on 10 opposite sides thereof, bolts of high elastic limit metal passing through said rail ends and bars, and nuts on said bolts, of lock

washers between the joint bars and the adjacent nuts, said lock washers having a circular form with wave-like bends therein to resist the compression caused by tightening said nuts and the passing of rolling stock and made of metal, as specified herein, capable of withstanding without flattening a 15 compressive force greater than the elastic limit of said bolts.

In testimony whereof, I have subscribed my name.

ROBERT L. COCHRANE.
